[57] **CLAIM**

The ornamental design for a bud vase, substantially as shown and described.

DESCRIPTION

FIG. 1 is a perspective view of a bud vase showing my new design;

FIG. 2 is a reduced top plan view thereof;

FIG. 3 is a reduced front elevational view thereof;

FIG. 4 is a reduced bottom plan view thereof.

The pattern of the alternating flowers repeats uniformly around the sides of the bud vase.
